SHOWER CURTAIN POCKET

Carlos N. Villaran, 5150 Sutton St. NW,
Washington, D.C. 20016

Filed Feb. 19, 1971, Ser. No. 117,183

Term of patent 14 years

Int. Cl. D23—02

U.S. Cl. D6—89

FIG. 1

FIG. 2

FIG. 4

FIG. 3

FIG. 5

FIG. 1 is a front perspective view of a shower curtain pocket showing my new design, the diamond configuration shown broken away for convenience of illustration is continuous;

FIG. 2 is a side elevational view thereof, the opposite side being identical;

FIG. 3 is a rear elevational view thereof;

FIG. 4 is a bottom plan view thereof; and,

FIG. 5 is a front perspective view thereof on a reduced scale showing my design in a position of use, the shower curtain being shown for purposes of illustrating environmental use.

I claim:

The ornamental design for a shower curtain pocket, as shown and described.
